(57) **CLAIM**

The ornamental design for a contact for a connector, as shown and described.

DESCRIPTION

FIG. 1 is a front perspective view of a contact for a connector showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The grey-fill shading is used as an aid to represent surface contour. The broken lines immediately adjacent to the shaded area represent the bounds of the claimed design and form no part thereof. The broken lines within the solid line circles form no part of the claimed design.
